UNITED STATES PATENT OFFICE.

AUGUSTINE V. D'COSTA, OF MATANZAS, CUBA.

CIGARETTE-PAPER.

SPECIFICATION forming part of Letters Patent No. 252,437, dated January 17, 1882.

Application filed June 30, 1881. (No model.)

To all whom it may concern:

Be it known that I, AUGUSTINE V. D'COSTA, a subject of Great Britain, residing at Matanzas, Cuba, have invented certain new and useful Improvements in Cigarette-Papers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a perspective view of cigarette-papers constructed in accordance with my invention and bound in book form, and Fig. 2 is a detached view of one of the sheets of paper.

The present invention has relation to certain new and useful improvements in cigarette-papers for making cigarettes; and it consists in providing one edge of such paper with a material or composition capable of igniting by friction, so that when the cigarette is rolled 25 and made it may be readily lighted by rubbing it over a frictional surface, as hereinafter more fully described.

In the accompanying drawings, A represents the cigarette-paper of the usual rectangular form, having applied to one of its short edges an ignitable material, a.

The composition may be applied by a brush or by suitable machinery adapted for the purpose, and is preferably in a liquid or soft state when so applied. It is preferred that a composition be employed analogous to that used in what are denominated "safety-matches," or, to more fully explain, what I consider as preferable is a composition which will ignite by 35 friction only when rubbed on a surface especially prepared for the purpose, so that there will be no danger from the accidental ignition

of the composition while the papers are being carried in the pocket. For convenience of carrying these papers A, thus prepared, they are 45 bound in book form, as shown at B, similar to the books of cigarette-papers in common use. This book B has upon one of its sides a composition tablet, b, having a frictional surface, so that after one of the papers A has been 50 torn from the book and rolled up with tobacco into a cigarette, by rubbing the prepared end thereof over the tablet b it will quickly and effectually ignite the end of the cigarette.

The composition that I prefer using or applying to the edge of the paper consists of the following ingredients: chlorate of potassium, one ounce; sulphuret of black antimony, one-half ounce; finely-powdered glass, about one-quarter of an ounce, with sufficient glue or other 60 suitable viscous or glutinous substance to form the whole into a thin paste.

The tablet b, I cover with a composition consisting of phosphorus amorph, one ounce, and sulphuret of black antimony, one-sixteenth 65 of an ounce, with sufficient glue to make it into a thin paste, when it may be put on the surface of the tablet with a brush or other suitable means, and, if desired, a small quantity of powdered glass may be added.

Having now fully described my invention, what I claim as new, and desire to secure by Letters Patent, is—

As an improved article of manufacture, a cigarette-paper having applied to one of its 75 edges a composition capable of igniting by friction, substantially as and for the purpose set forth.

In testimony whereof I affix my signature in presence of two witnesses.

AUGUSTINE V. D'COSTA.
